UNITED STATES PATENT OFFICE.

WILLIAM T. PYLE, OF DES MOINES, IOWA.

GATE AND LATCH.

1,369,300.

Patented Feb. 22, 1921.

Application filed February 17, 1920. Serial No. 359,345.

To all whom it may concern:

Be it known that I, WILLIAM T. PYLE, a citizen of the United States, residing at Des Moines, in the county of Polk, State of Iowa, have invented certain new and useful Improvements in Gates and Latches; and I do hereby declare the following to be a full, clear, and exact description of the invention, such as will enable others skilled in the art to which it appertains to make and use the same.

This invention relates to mechanically operated gates and the latches therefor, and more especially to those wherein the gate is mounted on a horizontal transverse pivot and is operated by a weight; and the object of the same is to improve the means for actuating the gate from a distant point and causing it to latch automatically when it changes its position.

A feature of the invention is its adaptability whereby the gate may be caused to open or to close automatically when unlatched, and yet at any time it may be adjusted to operate in the opposite direction. This adaptability renders the gate useful as a means for releasing or confining stock anywhere on the farm, by operating the actuating mechanism from one central point. Also it is possible to use the gate across a railway line or across a road which crosses a railway line, and operate it by the movement of the train.

Other features of the invention are its extreme simplicity, economy, reliability, and durability; as well as the fact that it can be erected by the purchaser at any desired point and will remain in successful operation indefinitely. The gate cannot sag and needs but a single post, and when it is closed there is no tendency to cant such post. The structure has no springs or ratchets to get out of order, is not susceptible to wind or weather, and rises out of the mud and snow rather than swinging through it; and its latching mechanism is such that it cannot be tampered with by the stock.

Details are set forth below, and attention is invited to the drawings wherein:

Figure 1 is a side elevation of this gate closed.

Fig. 2 is a detail of the gate post and another post, and the actuating mechanism.

Fig. 3 is a detail showing how the inven-

tion may be amplified by the addition of a safety latch at the free end of the gate.

The main or gate post 1 is preferably of channel steel rising vertically from a foundation 2 as of concrete seated in the ground and perhaps braced by a top bar 3 from which an inclined brace 4 leads downward to an anchor 5 on or in the ground behind the foundation. The main post will stand at one side of a roadway, and at the other side is a fence post P from which may lead a line of fencing F, this post carrying guides G and the roadway probably having a rest R adjacent this post on which the free end of the gate rests when it is closed. Fencing may also be led from the main post around the operating mechanism and brace, and to the left in Fig. 1, although it is not so illustrated herein. I have described the gate as standing across a roadway, although it might be disposed across a railway track. The gate itself is composed of a main bar 6 extending across and pivoted at 7 to the gate post 1, its outer and longer arm carrying the gate panel which is herein shown as made up of slats and pickets crossing and pivoted to each other and to the main bar and the post 1, and the panel also includes a bottom bar 9, which, like the top bar, is preferably made double so that the ends of the pickets may be pivoted between or within it, the outer end of the bottom bar resting on the rest R when the gate panel stands closed across the roadway as seen in Fig. 1. However, the specific construction of the gate panel is not important, excepting that by preference it hangs from the main bar 6, and when closed the outer end of the gate stands between the guides G on the post P so that stock may not push the gate to one side or the other, nor wind or storm move it out of its proper position. The gate is opened by the movement of the main bar 6 on its pivot 7 whereby the panel is raised as the bar 6 rocks. It is therefore apparent that the gate structure is mounted on a transverse horizontal pivot and does not swing at all.

The outer or shorter arm of the main bar carries a weight 10 which may be a box containing stones or other heavy articles, or may be adjustably mounted on this arm as by means of a bolt 11 engaging one of the perforations 12 in the arm so as to set the weight

nearer to or farther from the pivot 7. In these or in other ways the weight is therefore adjustable. As shown in Fig. 1 it is intended that the weight shall overbalance the gate so that normally it opens the same, but it is obvious that if the weight be made lighter or set nearer to the pivot, the gate will overbalance the weight so that the gate will normally close. The difference between the weight and the gate should be slight, because it is this difference which is to be overcome by the operator when actuating the mechanism hereinafter described, but it will be obvious that whether the weight overbalances or underbalances the gate, the action in one direction will be automatic and therefore the action in the other direction must be manual. The manual means is herein shown as a rope 13 leading upward from a point 14 on the rear arm of the main bar over one of a pair of pulleys 16 under the top bar 3, and thence to a remote point where this rope carries a handle 17 herein shown as a ring. In Fig. 2 the remote end of the rope 13 passes over a pulley 18 carried by a post 19 disposed alongside the roadway some distance from the gate, and it is to be understood a duplicate rope 13 passes over the other of the two pulleys 16 and is led in the other direction along the roadway to a similar post and its handle 17. Downward movement on the handle raises the weight and depresses the gate. If the rope 13 is attached to a point 15 on the inner arm of the main bar 6, downward movement of the handle would open the gate. That is the arrangement which would be followed when the weight is less than that of the gate.

A latch 20 is pivoted at 21 to the gate post 1 and has a notch 22 in its lower end adapted to engage over a pin 25 in the rear arm of the main bar 6, and a trip rope 23 leads from a point 24 on this latch over one of a pair of pulleys 26 and alongside the roadway over a pulley 28 on the post 19 to another handle 27 here shown as a cross bar. The latch falls by gravity into engagement with the pin 25, but a stop 29 prevents it from dropping too far. When the cross bar handle 27 is drawn upon, the trip rope raises the latch. Otherwise the latter is useful for holding the gate closed when the weight is heavier than the gate and tends normally to open it.

By preference I also make use of a second latch 30 pivoted at 31 to the gate post 1 at about the point shown and having a notch 32 adapted to engage the pin 25 as will be explained, a rope 33 connecting this latch at the point 34 with a point 35 on the first latch 20 so that when the latter is raised the second latch is also raised. Thus a sudden pull on one of the cross bar handles 27 draws on a trip rope 23 and raises both latches so that the gate is free to rise to open position

or descend to closed position. It moves automatically one way or the other according as the weight is set. A pull on the ring-shaped handle 17 draws on the rope 13 to actuate it in the reverse direction. Therefore a person approaching along the road first trips the latch and allows the gate to open, and after he has passed through he draws on the ring and closes the gate behind him. If the gate is used across or alongside a railway, means will be provided whereby the approaching train actuates the trip rope to permit the gate to open and then actuates the other rope to close the gate, and between the moments of actuation the train will pass through the open gate. Also if the gate closes a field where stock is housed and the ropes lead to a quite distant point, as perhaps the farm house, the owner without leaving his house can trip the latch and permit the gate to open any time he desires to release the stock from such field, or can draw on the other rope and close the gate after the stock has collected in the field in the evening.

The operation above is based on the assumption that the weight overbalances the gate. When the weight is set farther inward or is rendered lighter, the rope 13 must be attached to the point 15 on the main bar 6 inward of its pivot 7 because now when the trip rope is drawn on the gate closes automatically whereas it is opened manually. With the weight heavier than the gate, no latch 30 is absolutely necessary. With the weight lighter than the gate, this latch becomes indispensable but the other latch 20 is serviceable to prevent stock putting their noses through or under the gate at its free edge and raising it. Some animals might have the instinct to open a gate at its free edge, but they would hardly pass behind the gate post and endeavor to operate the mechanism there. While I have herein described ropes for tripping the latch or latches and for moving the weight, it is obvious that these elements might be wires or chains or it is possible that means for performing this service electrically from a distance might be substituted without departing from the spirit of the invention.

In Fig. 3 the invention is amplified to add a safety latch to the free end of the gate. As therein shown, this latch consists of a long spring 40 secured at 41 to the gate, leading upward and passing through a loop 44 on the gate, then bent sharply inward at an angle to form a working face 42 adapted to engage with a keeper or catch 45 on the post P, and a cord or wire 43 connects the upper end of this latch with the latch 20 or perhaps with the stop 29 as shown. With this addition the gate acts precisely as above described, but its free end is positively latched to the post P so that even if an animal

should put his head into or through the gate and lift on it he could not raise it high enough to disengage the guides G and therefore he could not force the gate open either 5 by raising it or pushing it aside. This safety latch is tripped by the tripping movement of the other latch and therefore it needs no actuating mechanism of its own.

What is claimed as new is:

- 10 1. A gate structure comprising an upright fixed post, a main bar pivoted across said post, a gate panel hung on its inner arm and a weight on its outer arm, a pin through the outer arm of said bar, latches pivoted to 15 the post and adapted to engage said pin when the gate is raised or lowered respectively, means connecting said latches to cause them to rise in unison, a stop on the upper latch to limit the descent of both latches, a 20 trip rope leading from the upper latch to a remote point, and a gate operating rope leading also to a remote point.

2. In a gate structure, the combination with a gate post, a main bar pivoted across the same, a gate panel on its inner arm, a weight on its outer arm, and means for adjusting the latter to permit the automatic opening or closing of the gate at will; combined with two latches whereof one drops 30 into engagement with said outer arm in either extreme position, means for causing them to rise in unison, tripping means leading from them to a remote point, and an operating rope leading from said point over 35 pulleys to the gate structure and attached to said top bar selectively at a point either side of its pivot according as said weight is adjusted.

3. A gate structure comprising an upright fixed post, a main bar pivoted across said post, a gate panel hung on the inner arm of said bar, and a weight on the outer arm of said main bar adapted to overcome the weight of the gate and raise the latter; of a 45 pin in said outer arm, a latch pivoted to the main post and having a notch in its head for engagement by said pin when the gate is closed, a stop supporting said latch while the gate is open, and ropes leading from this 50 arm and the latch to a remote point for operation of the gate.

4. A gate structure comprising an upright fixed post, a main bar pivoted across said post, a gate panel hung on the inner arm of said bar, a weight on the outer arm of said main bar adapted to overcome the weight of the gate and raise the latter, a pin through the outer arm of said bar, latches pivoted to the post and having notches adapted to engage said pin when the same is raised or 60 lowered respectively, means connecting said latches to cause them to rise in unison, a trip rope leading from the uppermost latch to a remote point, and an operating rope leading from the outer arm of the bar also 65 to a remote point.

5. In a gate structure, the combination with a gate post, a main bar pivoted across the same, a gate panel on its inner arm, a weight on its outer arm, and means for adjusting the weight to permit the automatic opening or closing of the gate at will; combined with means engaging said outer arm for latching the gate in either extreme position, tripping means leading from said 70 latching means to a remote point, and an operating rope leading from said point over pulleys to the gate structure and attached to said top bar selectively at a point either side of its pivot according as said weight is 75 adjusted.

6. In a gate structure comprising a pair of posts, a main bar pivoted across one of them, a gate panel hung on the inner arm of this bar, a weight on its outer arm to overbalance the gate, a latch holding the said outer arm raised and the gate closed, and means for operating said latch from a remote point; combined with a catch on the other post, a spring latch on the free end of 85 the gate adapted to engage beneath said catch as the gate closes, and a wire connecting this latch with that first named so that the gate will be unlatched at both points 90 simultaneously.

In testimony whereof, I affix my signature, in the presence of two witnesses.

WILLIAM T. PYLE.
